Attorney

UNITED STATES PATENT OFFICE.

WILLIAM J. WHITEHEAD, OF SPRINGFIELD, MISSOURI.

CHAIR.

1,182,125.

Specification of Letters Patent. Patented May 9, 1916.

Application filed November 25, 1914. Serial No. 873,888.

To all whom it may concern:

Be it known that I, WILLIAM J. WHITEHEAD, a citizen of the United States, residing at Springfield, in the county of Greene and State of Missouri, have invented certain new and useful Improvements in Chairs, of which the following is a specification, reference being had to the accompanying drawings.

10 This invention relates to chairs, and more particularly to improved means for mounting the chair back, seat, and leg support whereby the same may be adjusted relative to each other.

15 The invention has for its primary object to provide a chair having the above noted general structural characteristics which is particularly designed for use upon vehicles, whereby the same may be very easily and 20 quickly adjusted so as to occupy a minimum of space, or extended so that the occupant may recline thereon.

25 The invention has for another and more specific object to provide an improved construction of hinge joint which connects the several adjustable parts of the chair.

30 It is another object of my invention to produce an adjustable chair or seat which is exceedingly simple in its construction, 35 may be manufactured at small cost, and is highly serviceable and convenient in practical use.

With the above and other objects in view, the invention consists in novel features of construction, combination and arrangement of parts as will be hereinafter referred to and more particularly pointed out in the specification and claims.

For a full understanding of the invention, 40 reference is to be had to the following description and accompanying drawing, in which—

Figure 1 is a side elevation, partly in section illustrating an adjustable chair constructed in accordance with the preferred embodiment of my invention; Fig. 2 is a section taken on the line 2—2 of Fig. 1; and Fig. 3 is a section taken on the line 3—3 of Fig. 1.

50 Referring in detail to the drawing, 5 designates two similar side frames which are suitably secured upon the respective side walls of the vehicle body. Each of these side frames includes a horizontally disposed bar 6 and an upwardly projecting extension 7 at one end of said horizontal bar. The

particular purpose of this frame extension will be hereinafter fully explained.

The seat of the chair, shown at 8, is provided at opposite sides and adjacent to its forward end with the depending brackets 9 which are formed with inwardly projecting hollow tapering cylindrical bosses 10. The forward end of the seat 8 is also provided with similar bosses 11. Each of the horizontal portions 6 of the side frames 5 is provided adjacent its forward end with an opening 12 through which a threaded rod 13 extends. Nuts 14 are threaded upon this rod and disposed above and below the horizontal bar 6. Upon the upper end of the rod 13 the male hinge member 15 is formed, said member being provided with the frustoconical extension 16 which is designed for engagement in the hollow boss 10 formed upon the depending bracket 9. This extension 16 is centrally provided upon its end wall with an internal bearing sleeve 17 to receive the hinge bolt 18. This bolt is also adapted to extend through an opening 19 provided in the base wall of the boss 10. The annular walls of this boss and the extension 16 are disposed in parallel relation and between the same a bushing or gasket 20, preferably of sheet copper is disposed. Any other suitable friction material may, however, be substituted for this copper sheet. The inner end of the hinge bolt 18 is formed with an enlarged head 21, between which and the end of the bearing sleeve 17, a washer plate 22 is arranged. A heavy coil spring 23 is disposed upon the sleeve 17 between this washer plate and the base of the hollow extension 16, said spring acting to normally force said extension against the friction sheet 20 and hold said friction sheet tightly against the walls of the boss 10. Upon the outer end of the pivot bolt 18 a nut 24 is threaded for the purpose of securely clamping the parts together.

As above stated, the forward end of the seat at opposite sides is provided with inwardly extending hollow bosses 11, and in these bosses the male hinge members on one end of a leg rest, indicated at 25, are adapted to be engaged and secured in precisely the same manner as that above described. The detail construction of this hinge joint between the leg rest and the seat will not therefore be further referred to. The seat 8 is also formed at its rear end and upon opposite sides with the outwardly project-

ing hollow bosses 26. The back 27 of the chair has formed upon its lower end and at opposite sides the solid conically shaped projections 28, each of which is provided in its outer face with a recess 29. The extension 7 on each of the side frames 5 is provided in its opposite faces with the tapering recesses or seats 30 and 31, which are designed to receive the extensions 26 and 28 10 on the seat 8 and back 27 respectively of the chair. The projection 26 of the chair seat is formed with a sleeve 32 through which the hinge bolt 33 is disposed. The upper end of the chair frame 7 is provided with an 15 opening 34 and the conical projection 28 on the chair back with an opening 35. These openings coincide with the bore of the sleeve 32 and through the same said hinge bolt extends. A head 36 is formed on 20 the inner end of the bolt 33, between which and the base of the hollow extension 26 on the chair seat the coil spring 37 is arranged. A sheet of friction metal 38 is disposed between the peripheral face of the conical extension 28 of the chair back and the opposed 25 surface of the recess 31. A nut 39 is threaded up the outer end of the bolt 33, whereby the several parts may be securely clamped together and held against relative movement.

The free end of the leg rest 25 may be provided with a foot pad, indicated at 40, preferably removably attached to the leg rest and extending outwardly therefrom 30 when the leg rest is not in use. The upper end of the chair back 27 is equipped with a removable and adjustable head rest 41, which may be mounted and adjusted in any 35 approved manner. This head rest, as well as the chair back, the seat, and the leg rest, 40 are provided with suitable cushions, indicated at 42.

From the above description taken in connection with the accompanying drawing, 45 the construction, manner of operation, and several advantages of my invention will be clearly understood. When it is desired to adjust the chair, the hinge bolts 18 and 33 at opposite sides of the chair are loosened.

50 The nuts 14 are then adjusted upon the rod 13 to move said rod vertically and dispose the seat 8 in the desired inclined position with respect to the supporting frames 5. The nuts 14 are then adjusted into clamping adjustment against the frame bar 6 to 55 securely hold the rods 13 against further movement. The nuts are then threaded inwardly upon the bolts 18 against the brackets 9 so as to draw the extensions 16 60 on the hinge members 15 into the hollow bosses 10 to tightly clamp and bind the metal friction sheet 20 between the opposed walls thereof. The chair back 27 is now tilted to the desired position. The coil 65 springs 37 have sufficient tensile strength to

hold the chair back in its adjusted position against casual movement until the nuts 39 can be adjusted to tightly clamp the several parts of the hinge joints together, whereby the chair back will be rigidly supported upon the upper ends of the frames 5. The leg rest 25 is now adjusted with respect to the seat 8 in a similar manner.

It will thus be seen that I have devised an improved construction of hinge joint between the several adjustable parts of the chair which will also securely hold the several parts against relative movement upon the hinge bolts when the nuts are securely tightened thereon. The necessity of providing additional locking or holding means is consequently avoided. It will therefore be apparent that my improved chair may be manufactured at comparatively small cost, and is also highly durable and reliable in practical use.

While I have referred to the chair as particularly designed for use upon vehicles, it will be understood that the same may also be used as an ordinary chair and readily moved from place to place.

While I have above described the preferred form, construction, and arrangement of the several elements employed, it will be understood that the device is, nevertheless, susceptible of considerable modification therein, and I therefore reserve the privilege of resorting to all such legitimate changes as may be fairly embodied within the spirit and scope of the invention as claimed.

What I claim is:

1. A hinge joint of the character described including a frusto-conical female member and a complementary male member of hollow form, said members each being axially provided with an opening and the male member having a sleeve projecting inwardly from said opening, a bolt loosely disposed through the axial openings of the coupling members and provided with a head on one end, a frusto-conical metal friction sheet disposed between the contiguous body walls of the coupling members, a nut threaded upon the other end of the bolt, and a spring arranged within the hollow male member upon the sleeve thereof acting to hold the coupling members in frictional engagement with the friction sheet when the nut is loosened.

2. A hinge joint of the character described including a stationary part provided with tapering recesses in its opposite faces and having a bolt receiving opening, movable parts one of which is provided with a conical shaped hollow boss for engagement within one of said recesses, the other movable part being provided with a solid conically shaped projection for engagement within the other of said recesses, said solid

projection having a recess in its outer face, said boss and projection being provided with openings to coincide with said first named opening, a bolt disposed through said coinciding openings and on one end, a metal friction sheet arranged between the solid projection and the wall of one of said recesses, a nut threaded upon one end of said bolt for clamping engagement against the solid projection and disposed within the recess thereof, and a coil spring arranged between the head of the bolt and the other

movable part of the joint and coöperating with said bolt to move the same in one direction when the nut is loosened and hold 15 said boss and projection against casual movement with respect to the stationary part.

In testimony whereof I hereunto affix my signature in the presence of two witnesses. 20

WILLIAM J. WHITEHEAD.
